UNITED STATES PATENT OFFICE.

CHARLES H. HOWLAND-SHEARMAN, OF INDIANAPOLIS, INDIANA, ASSIGNOR, BY DIRECT AND MESNE ASSIGNMENTS, TO THE UNITED BROOM COMPANY, OF KOKOMO, INDIANA, A CORPORATION OF MAINE.

BROOM-PRESS.

1,324,153.

Specification of Letters Patent.

Patented Dec. 9, 1919.

Application filed January 16, 1917. Serial No. 142,714.

To all whom it may concern:

Be it known that I, CHARLES H. HOWLAND-SHEARMAN, a citizen of the United States, residing at Indianapolis, in the county of Marion and State of Indiana, have invented a certain new and useful Improvement in Broom-Presses, of which the following is a specification.

My invention relates to improvements in machinery for automatically manufacturing brooms such as shall be adapted to supplant the prevailing methods of manual manufacture, and its particular objects are:

First, to supply a broom press capable of automatically bringing together broom corn, or similar materials, when cut to proper lengths and fed into said machine, so as to form the shoulder of the broom, ready for sewing to complete same for the broom; second, to supply a broom press particularly adapted to collect together brooms of that style of mechanically made brooms having detachable handles, such bringing together of said brooms being completed by 25 the press before any handles are applied to same; third, to provide a broom press mechanism adapted to automatically apply upon the broom materials a ring which shall serve to constrain the same in a state of 30 high compression, instead of the previous methods by binding the material by wire upon handles as in manual manufacture, or by rigidly clamping the same between riveting clamps or screwed retaining members 35 as in mechanical manufacture; fourth, to provide a broom press embodying automatic mechanisms adapted to respectively receive the rings for the quantity of broom corn and secure each bunch of broom corn 40 together in the press; a mechanism adapted to receive individual charges of broom material for making the individual brooms of uniform size, and mechanism adapted to automatically withdraw and convey from 45 said broom press the newly formed brooms, and, fifth, to provide a broom press embodying mechanism by which it shall be adapted to be interchangeably operated for the formation of various standard sizes of brooms, 50 with equal efficiency in collecting and bringing together the material for the respective size of brooms.

I attain the objects stated by means of the construction illustrated in the accompanying drawings, in which—

Figure 1 is a side elevation of my broom press; Fig. 2 is a top plan view of same; Fig. 3 is an enlarged detail of the clutch release mechanism near the rear end of the clutch shaft; Fig. 4 is an enlarged detail 60 of the forward end of the same clutch mechanism; Fig. 5 is an end elevation of the broom press showing the relative position of the motor, power gears, crankshaft and crank; Fig. 6 is an enlarged detail taken 65 partly in section showing the manner in which the rear section of the crankshaft is journaled in a bearing in the rear end of the intermediate section thereof; Fig. 7 is a top plan view of the compacter mechanism; Fig. 8 is a transverse section, taken 70 on the line 8—8 of Fig. 2 looking in the direction of the arrows, showing the automatic broom corn feeding mechanisms, ring feeding mechanism, jaw mechanism and 75 broom corn stripping and conveying mechanisms, with the contact mechanism of the power clutch; Fig. 9 is an enlarged top plan view of one of the larger sizes of dies adapted to be interchangeably used instead of the 80 smaller size of die shown in Fig. 2; Fig. 10 is an elevation of the same die block shown in Fig. 9; Fig. 11 is an enlarged detail of the automatic release of the ring feed mechanism; Fig. 12 is an enlarged detail 85 showing a modified form of the broom corn feeding mechanism, in which I use my same floor plate below the dies instead of above the dies as in Fig. 8, thus permitting the broom materials to gravitate directly 90 into the required position for compressing them into the broom; Fig. 13 is an enlarged group detail showing the mechanism of the automatic broom removing linkage; Fig. 14 is an enlarged central longitudinal section 95 of the floor plate, used for alining upon an even plane the broom materials for each broom as same are fed into the press; Fig. 15 is an enlarged partly sectional elevation of the straw inserter roll crank, taken on 100 the line 15—15 of Fig. 1; and Fig. 16 is an enlarged detail, partly in transverse section and partly in elevation taken on the line 16—16 of Fig. 1, showing the press frame,

the die block guides therein, and part of the straw inserter linkage. Fig. 17 is an enlarged detail view partly in section of the compacter frame, showing the detent bars 5 and pins in operative position, on the line 17-17 in Fig. 7.

Similar numerals refer to similar parts throughout the several views.

Referring to Figs. 1, 2 and 5, 1 is the press frame, which is supported on legs 2, 3 and 4, and having securely mounted thereon the motor 5, the axle 6, which bears on its front end the motor pinion 7, preferably of the noiseless fiber type. Said motor pinion meshes with the intermediate gear 8, on the intermediate shaft 9, which is journaled in the front pedestal 10 and rear pedestal 11 superiorly secured upon the table 12 of said press frame 1. A set collar 13 prevents rearward endwise motion of said intermediate shaft 9 and forward endwise motion of same is prevented by the intermediate pinion 14, keyed thereon, and cheeking against said rear pedestal 11, said intermediate pinion being also preferably of a noiseless fiber construction. The flywheel 15 is keyed upon the extreme rear end of the intermediate shaft 9, for the purpose of placing intermediate to said flywheel and the intermediate gear 8 the high pressure delivery torque of the intermediate pinion 14, found by experience to be indispensable for the successful operation of my invention.

The intermediate pinion 14 meshes with the crank gear 16 journaled on the rear section 17 of the crankshaft, of which the rear end turns in the rear yoke pedestal 18 of the rear yoke 19, supported on the leg 2, and the forward end of which, as especially shown in Fig. 6, is provided with a reducing projection 20, which turns in the cavity 21 formed in the rear end of the intermediate section 22 of the crankshaft. The fixed clutch disk 23 is keyed upon the forward end of said rear section 17 of the crankshaft and is provided with a tooth 24 adapted to be engaged by the corresponding tooth 25 upon the movable clutch disk 26, keyed upon the rear end of said intermediate section 22 of the crankshaft, which latter turns at its rear end in the clutch pedestal 27 and at its forward end in the crank pedestal 28, both secured upon the sloping platen 29 of the frame 1.

The clutch lever 30 is journaled upon the pin 31 in the bracket 32 secured to said leg 2 and is provided at its top with a fork 33, having trunnion pins 34 adapted to engage the channel 35 formed in the periphery of the movable clutch disk 26. The lower end of said clutch lever 30 is provided with a slotted fork 36 adapted to engage the crank pin 37 fixed in the crank crank 38 keyed upon one end of the clutch shaft 39, turning 65 in the clutch block 40, secured upon leg 2

and a tension spring 41 respectively secured to said leg 2 and said clutch lever 30 causes the latter to normally throw the movable clutch disk 26 into engagement with the fixed clutch disk 23.

Referring to Figs. 1, 2 and 5, the set collar 42 secured upon the intermediate section 22 of the crankshaft and checked against the crank pedestal 28 prevents longitudinal movement of said intermediate section in one direction while the crank disk 43 keyed upon the forward end of said intermediate section and cheeking upon the front face of said pedestal prevents longitudinal movement of shaft-section 22 in the opposite direction. Said inner crank disk 43 is united to the outer crank disk 44 by the crankpin 45 respectively secured thereto by the nuts 46 and 47, so as to give a perfectly firm bearing for the crank link 48. The outer crank disk 44 is keyed upon the outer section 49 of the crankshaft which is journaled in the brake pedestal 50 borne on the front yoke 51 of the leg 2 and the front end of said section 49 has keyed thereon the friction 90 brake 52, the function of which is to prevent the crankshaft parts from moving by inertia beyond the point to which they are carried by the power gears, after disconnection of the clutch disks. The crank link 95 48 has provided thereon the fork 53 which is articulated by the cross head pin 54 to the tang 55 of the power cross head 56. Said power cross head 56 is preferably made as shown in the views referred to, in the 100 form of an ordinary piece of shafting adapted to slide smoothly in the bored brackets 57 and 58 secured upon the table 12 of the frame 1.

The cross head collar 59 is rigidly secured upon said power cross head 56 and bears 105 dependently secured to its under side the cam bolt 60, attached to and supporting one end of the wedge plate 61, the opposite end of which is attached to and supported by the wedge bracket 62, also rigidly secured to said cross head 56. The trunnion block 63 slides freely upon the power cross head 56 but is kept from turning laterally thereon by the feather 64 secured in said power 110 cross head which also slidably engages with the bored bracket 58. Said trunnion block 63 has trunnion pins 65, to the upper of which is jointed the superior cross head link 66, and to the lower of which is jointed 115 the inferior cross head link 67, which is provided with a slot 68 adapted to give clearance passage therethrough to the bolt 60 for the full motion thereof, when carried by the stroke of said cross head collar 59, as the 120 same is actuated by the power cross head 56 upon revolution of the crank disks 43 and 44. The ends of said cross head links 66 and 67 opposite to the trunnion block 63 are jointed by the pin 69 commonly to the 130

outer arm of the crank-arm 70 and to the inner fork 71 of the synchronizing link 72. Said inner crank-arm 70 is journaled upon a pivot-pin 73 to a bracket 74 secured 5 to frame 1 and its outer arm projects through the inner opening 76 leading from the inside to the outside of said frame, as especially shown by Fig. 2. The outer arm of said synchronizing link 72 is jointed by 10 the pin 77 to the outer end of crank-arm 78, the outer arm of which likewise makes egress through an opening 79 in the frame. It will be clear from Fig. 2 that the inner crank arm 70 is greater than a right angle, 15 but that the outer crank arm 78 is correspondingly less than a right angle, in order that the simultaneous actuation of the crank-arms in the direction of the arrow by the synchronizing link 72 shall operate 20 them equally, but in opposite directions, both toward a common center. Said outer crank arm 78 is journaled upon the outer pivot pin 80 arranged in bracket 81, secured to frame 1. The inner end of said inner 25 crank arm 70 is jointed by the inner knuckle pin 82 to the inner straight link 83, the inner end of which is in turn jointed by the inner thrust pin 84 to the inner thrust block 85, secured upon the inner die block 86 sliding in the ways 87 within which it 30 is secured by the cap plates 88; the inner end of the outer crank arm 78 is jointed by the outer knuckle pin 89 to the outer straight link 90, the inner end of which is jointed 35 by the outer thrust pin 91 to the outer thrust block 92 secured to the outer die block 93 running in the ways 94 within which it is held by the cap plates 95.

Referring to Fig. 2, in connection with 40 Figs. 9 and 10, the several sizes of dies, 96, used by me in my broom press to form brooms for the respective trade-sizes of brooms all fit interchangeably in the respective die blocks 86 and 93, so that said dies face each other 45 with their broom forming configurations registering oppositely as each of said die blocks is driven toward the opposite die block when the respective opposing toggles thereto attached are simultaneously actuated 50 by the synchronizing link 72. Said dies are retained in the die blocks by fishtails 97 and are held securely upon their seats by die bars screwed to said die blocks, as 98, Fig. 2. Oppositely registering ring slots 99 55 are provided in said die blocks, adapted to admit the broom rings which, upon entrance therebetween, drop behind the abutment shoulders 100 upon the ring ledges 101, upon which they are securely held by the springs 60 102 secured by screws 103, to the die. As said die blocks 86 and 93 are brought together with an oval ring (as 104, Fig. 8) held upon said ledges between said dies, the ring is first flattened along the straight faces 65 104^a and then given the final curved ends

by the forming curves 105, 106, formed upon the interior edges of the tool steel die-liners 107, 108, secured at either end of the die body 109, so as to give the resultant compressed brush a rounded oblong cross section at the point at which the ring is compressed upon same. The exterior edges of said die-liners 107, 108 have angular faces 110, 111 preferably of 45 degrees angularity for accommodating between same the corresponding angular faces of the tool steel abutment blocks 220, 222, which receive the thrust of the extreme ends of the ring, forming tangents to said curves 105, 106, as the dies close, as will be clear from Fig. 2. 75

As shown in Figs. 1 and 2, the parts of my broom press are arranged for the proper crank throw and stroke conditions to make a given standard size of brooms, but when it is desired to make a different standard 80 size of brooms, requiring a corresponding variation of crank throw, so as to produce a different thickness of the brush cross section, the crank pin 45 is shifted and passed through the holes 112 in the crank disks, 43 85 and 44, thereby giving a shorter crank radius and corresponding crank throw, and the dies are withdrawn from the respective die blocks 86 and 93 and replaced by dies of different size, such as those indicated in 90 Figs. 9 and 10, when the press, so readjusted, will properly form the altered size of 95 broom required. This provision for adapting my press to various sizes of brooms is one of much practical importance and has 100 been proved by experience upon actual machines to be quickly and reliably operative in its results.

Referring to Figs. 1, 2 and 8, the hand lever housing 113 is secured upon the front 105 of the frame in line with the central transverse axis of the toggle mechanism, and encloses the several elements which control the press's entire operation. The hand lever 114 is mounted in the bracket 115 upon the fulcrum 116, which is provided at its top with a handle 117 for governing the press operation. When the broom materials are admitted through the chute 118, supported by the circular frame 119, secured to the boss 115 120 on the broom ring chamber 121, they drop through the compacter 122 upon the resilient table 123 of the floor plate 124, provided with ears 125 through which the pin 126 is jointed to the floor plate link 127, in turn jointed by the pin 128 to the vertical arm of the floor plate bell crank 129, which is journaled upon the fulcrum pin 130 in the bracket 131 made integrally upon the floor 125 of the hand lever housing 113. The short arm of said floor plate bell crank 129 has fixed therein the pin 132 adapted to engage the closed slot 133 in the slot link 134, the lower end of which is jointed by the pin 135 to the curved crank-arm 136 of said hand 130

lever 114, the forked short arm 137 of which is jointed by the pin 138 to the ring feed bar 139, used for actuating my ring feed mechanism as hereinafter described. The hand lever housing 113 is provided with a central transverse aperture 140 through which the members 134, 136 and 137 operate with free clearance. The chute 118 shown in Fig. 8 and in slightly modified form in Fig. 12 is adapted to admit the broom materials for proper alinement upon the floor plate 124, prior to compaction of same within the broom ring. Said chute may be elongated to any desired height, so as to permit the broom materials to acquire sufficient gravitational momentum for their ready alinement upon impact, or it may be shortened if it be desired to insert the materials manually in individual broom charges through said chute and thus aline them upon the floor plate, or the chute 118 may be constructed with any desired number of internal apertures as shown by 141 Fig. 12 for the purpose of keeping separate the corresponding kinds of material employed in making the broom, this formation of the chute being used when manufacturing brooms of the type having fine hurl covering over coarser interior fillers. Fig. 14 details the construction of one of my standard forms of floor plate, in which the resilient table 123 is supported on springs 142, which keep its flanges 143, 144 normally pressed up against the retaining flanges 145, 146 so that said resilient table shall be flush with the top of the plate, and said springs 142 are retained at the base by the tool steel slide plate 147 secured by screws 148 to the floor plate 124, air apertures 149 being supplied to permit free passage of the air in the rise and fall of said resilient table 123. I frequently employ large sections of very open-pored rubber sponges in the cabinet 150 of the floor plate, for resiliently supporting said table 123 instead of the springs 142, both constructions being successful in operation. The function of the resilient table 123 is to yield sufficiently upon impact of the broom materials, when gravitated sharply upon the floor plate, so that upon the rebound of said member 123 it automatically alines any fibers which may have fallen in advance of other fibers of the broom. This function has been proven by experience to be of much value in the admission of a uniformly alined charge of broom materials to the machine.

Referring to Figs. 1, 7 and 8, the pin 151 joints the hand lever 114 to the compacter link 152, in turn jointed by the pin 153 to the compacter slide 154, sliding in the guide 155 formed integrally in the top of the hand lever housing 113, and a pin 156 joints to said slide the ratchet hook 157, adapted to engage the ratchet 158 on the compacter

yoke 159, secured upon the front ends of the wedge-rods 160, 161, by which the compacter is actuated as below explained. The compacter 122 is made as a hollow rectangular frame provided with crossbars 162, 163, secured to either side thereof, for the purpose of sustaining the central mechanism of said compacter. Four quadrangularly disposed bosses 164 on the compacter frame are adapted to receive the upper ends of the compacter rods 165, secured to the compacter by nuts 166. Long wedges 167, 168, engagedly sliding upon the respective guides 169, 170, at either end of the compacter frame, are secured at the inner ends of the wedge-rods 160, 161, and compression springs 171, 172 surrounding the rods 160 and 161 tend to normally push rearward said wedges 167, 168, and thus withdraw toward the compacter frame the compacter yoke 159 when the compacter is opening for reception of broom materials. After the reception of broom materials, the actuation of the handle 117 withdraws said compacter yoke 159, compressing said springs 171, 172, and causes said long wedges 167, 168 to push inward the short wedges 173, 174, secured on the outer ends of the plunger bolts 175, 176, sliding in the plunger sockets 177, 178. Each of said plunger bolts is provided with a collar as shown at 179, Fig. 7, and encircled by a compression spring 180, impinging against the fixed sleeve 181 secured within the inner end of the socket, thus keeping each plunger bolt, as 175, with its small wedge, as 173, normally pressed outward against its respective long wedge, as shown, Fig. 7. Each of said plunger bolts is also pierced by a slot 182 engaging the pin 183 driven through said fixed sleeve 181, which prevents the plunger bolt from turning. On the inner ends of the respective plunger bolts 175 and 176, vertical pins 184 and 185 are provided upon which are jointed the two sets of curved interlapping compacter fingers 186 and 187 on said pin 184 and 188 and 189 on said pin 185, the internal configuration of all of said four compacter fingers being so curved that when the compacter shall be compressed upon the broom materials, the fingers will take the position shown in Fig. 7 and combine to form an enclosed space between them, corresponding to the oval contour of the broom ring held in the die blocks below, as shown at 104, Fig. 8, through which the compacted materials are to be passed. The inner end of each of the compacter fingers is provided with a roll as 190, turning on a pin as 191, which rolls face each other and impinge upon the sides of the wedges 192, securely imposed on the top of each of the plunger bolt sockets as 178, with the result that, as each of the small wedges 173, 174 is forced

inward by the long wedges 167 and 168, the outer ends of the said compacter fingers 186, 187, 188 and 189 are forced apart, and the inner ends thereof are forced together upon the broom materials therebetween inclosed, which material is thereby compacted to the required density for its insertion through such a broom ring as 104 Fig. 8. Tubular spring return-members 193, 194, 10 hingedly jointed upon spring arms as 195, secured on the outer ends of each of said compacter fingers, draw said outer ends together and keep the rolls as 190 in constant contact upon the wedge 192, when the inward motion of the compacter yoke permits the plunger bolts 175 and 176 to fly outward, and thus the fingers of the compacter open for the reception of another charge. Detent bars 196, 197 each provided with 20 duplex spring bolts 198, 199, normally press down the respective detent pins 200, 201, so that the same shall engage in suitable holes in the respective compacter rods 160, 161 to hold the compacter mechanism locked in its compacted position as in Fig. 7 during insertion of the broom materials through the broom ring, but, upon the compacter being drawn down to the bottom of its vertical stroke by the compacter rods 165, said 25 spring bolts 198, 199 are forced upward by contact with the upper side of the frame 1, as indicated in Fig. 1, thereby simultaneously releasing both detent bolts 200 and 201, which permits the compacter yoke 159 30 to recede toward the frame and all parts of the compacter to return to their open positions for receiving another charge.

The preferred form of my invention, in which a compacter of the type of compacter 40 122 is employed, embodies what I term a broom corn inserter linkage, for the purpose of drawing down said compacter 122 after the compaction of each charge of materials and inserting the same through the 45 ring which is to be compressed thereon. This mechanism is clearly shown in Figs. 1, 2, 15 and 16, in which 202 is the roll crank brackets, inferiorly secured to the frame 1 and bearing therein the fulcrum pin 203, upon which are journaled the paired roll cranks 204 and 205, between the shorter crank arms of which is journaled upon the pin 206 cam roll 207 adapted to be actuated by the wedge cam 208 of the 50 wedge plate 61, the cranks having secured between them the adjusting yoke 209 pierced by the lock-nutted adjusting bolt 210, dependently sustaining the slide yoke 211, provided with four lateral ears, as 212, Fig. 15, 55 on the front and back thereof, embracing the smooth slides 213, along which the position of said slide yoke is variably fixed by said adjusting bolt, to regulate the motion imparted from the roll crank. The pin 214 60 in the slide yoke 211 joints the same to one

end of the broom corn inserter link 215, the opposite end of which is jointed by the pin 216 to the forked rock lever 217, secured upon the rockshaft 218, journaled in the brackets 219, 219^a, dependently secured to 70 either side of the frame 1. Paired rock links 221, 221^a are secured next to either of said brackets 219, 219^a upon the rockshaft 218, and, as especially indicated in Figs. 8 and 16, are jointed by the pins 223 to the duplex 75 compacter links 224, which are in turn jointed by the pins 225 to the compacter bases, as 226 Fig. 8, from which latter view the rear of the said compacter bases, with its links, has been broken away for clearness in drafting. The weight of the compacter is balanced by the counterpoise 227, the arm 228 of which is rigidly secured upon the rockshaft 218. The latter has secured upon its extreme rear end the 80 spring lever 229, jointed at its top by the pin 230 to the forked spring rod 231, riding in the spring bracket 232 and provided with strong compression springs 233, held under compression against said spring 85 bracket 232 by the spring cap 234. The function of said spring rod and spring lever is to accelerate the upward return of the compacter 122 after it has deposited each charge of broom materials through a ring 90 as 104 Fig. 8, and reopens to receive another charge after the release of the detents 200 and 201, as previously explained.

Referring to Figs. 2, 8 and 11, the ring feed bar 139 is jointed at its rear end by 100 the pin 235 to the forked short arm 236 of the duplex release lever 237, the two sides of which embrace the interstitial ring feed lever 238, commonly fulcrumed with said release lever on the pin 239 in the fork 240 105 of the ring feed bracket 241. The top of the ring feed lever 238 is jointed by the pin 242 to the plate link 243, in turn hinged by the rod 244 to the clamp 245 within which is secured the ring feed plate 246, provided 110 at its inner end with a curved jaw 247, having a contour adapted to fit the exterior of the oval rings 104, and of a thickness equal to one only of said rings, so that upon recedence of said ring feed plate 246, one 115 ring only from the gravitating pile of rings in the ring feed chamber 121 shall enter and fill the jaw of said ring feed plate. On either end of the rod 244 are secured brackets 248 and 249 through which telescope the 120 guide rods 250, 251, secured to the frame 1, encircled by springs 252 and 253, which normally tend to throw outward the ring feed plate 246 whenever the lever 238 is released. Said ring feed plate 246 rides upon the 125 hardened steel base 254 and is inclosed within the U-shaped cap plate 255, resting upon said base. Cap-plate 255 is provided with an aperture through which the broom rings are fed from chamber 121, and said cap is 130

provided in its lower or under surface with a channel 256 forming a passageway for the rings in their movement toward the dies.

- The duplex release lever 237 is provided 5 with brackets 257 upon the pin 258 on which is fulcrumed the release crank 259, provided with a fork 260 engaging interiorly the collar 261 and exteriorly the crown 262 of the acorn bolt 263, which is normally kept in 10 engagement with the socket 264 of said ring feed lever 238 by the spring 265 compressed between the release crank 257 and the lug 266. When the action of the hand lever 114, through the ring feed bar 139 throws 15 forward the ring feed lever 238, the release crank 259 makes contact with the release bolt 267, secured in the ring feed bracket 241, thus withdrawing the acorn bolt 263 from the socket 264 in said ring feed lever 238 and permitting said bolt to ride idle 20 over the face of the arc 268, which extends integrally flush with the face of said ring feed lever 238 and the latter, being thereby released, is instantly forced backward by 25 the springs 252 and 253 to admit another ring 104 to the mouth 247 of the ring feed plate 246, while the release lever 237 remains in its forward position until released by a return stroke of the handle 117.
- 30 Referring to Figs. 2, 3, 4 and 8, the bracket 249 bears an integrally dependent lug 269, in which is secured the tappet screw 270, adapted, upon forward motion of the hand lever 114, to contactively actuate the 35 rock link 271, secured upon the upper end of the rockshaft 272 turning in the vertical boss 273 integral upon the ring feed bracket 241. Upon the bottom end of said rockshaft is secured by the nut 275 the rock lever 276, the forked end 277 of which engages by the 40 pin 278 with the release hook 279, the opposite end of which engages with the clutch release link 280 journaled on the clutch shaft 39 and normally kept thrown behind the 45 clutch release crank 281 turning upon the fulcrum 282 secured to the under side of the frame 1, as shown in Fig. 2 by the action of the barrel spring 283, surrounding said clutch shaft and impinging against the collar 284 secured thereon, but capable of being withdrawn from engagement with said clutch release crank 281 by contact of said tappet screw 270 with said rock link 271, thus giving the parts the position shown in 55 Fig. 3, in which position the power clutch disk 23 is in engagement with the clutch disk 26, thus placing the press into full operation. The hub of said clutch release link 280 is bored to fit the clutch shaft 39 and is 60 engaged by the feather 285 secured in said clutch shaft. The motion of the said release link 280 is limited by the collar 286 also secured to said clutch shaft. The release crank 281 is actuated by the thrust 65 thereon of the vertical release bar 287 de-

pendently secured on the die block 93, with which release bar said crank is constantly kept in contact by the tension spring 288, secured between said bar and crank, as clearly shown in Fig. 3.

At the completion of each broom compressing cycle of my press, as the jaws open, said release bar, acting through its thrust upon said release crank and thereby actuating through the release link 280, the clutch 75 shaft 39, disengages and holds in disengagement the clutch 26 from the clutch disk 23, until another operation of the hand lever 114 shall have caused the reengagement of the clutch by action of said tappet 270 upon 80 said rock link 271. The manner in which the clutch disks are automatically engaged by the clutch lever 30 upon release of the said clutch shaft 39 is clearly stated in lines 55 to 70 page 2.

Ejecting and conveying mechanism is indicated by Figs. 1 and 2 and partly depicted in enlarged detail by Fig. 13. The ejector bolt bracket 289 is secured upon the die block 86 and is jointed by the pin 290 to 90 the ejector bolt 291 sliding in the socket link 292 and adapted to contactively engage the spring bolt 293, normally caused to protrude transversely within said socket link 292 by action of the compression spring 294 beneath the collar 295. The socket link 292 is jointed by the pin 296 to the ejector crank 297, journaled on the fulcrum 298 of the ejector bracket 299, the long arm of which is jointed by the pin 300 to the drop link 100 301, the opposite end of which is jointed by the pin 302 to the ejector lever 303 journaled on the fulcrum pin 304 in the bracket 305 secured upon the cross bar 306 of the leg 3. The shorter rear arm 307 of the ejector lever 303 is jointed by the pin 308 to the fork 309 of the spring bolt 310 surrounded by the compression spring 311 impinging beneath the spring bolt bracket 312 secured upon the frame 1 and the spring bolt is provided with a collar 313 at its upper end to limit the downward stroke of said spring bolt. The counterpoise 314 at the inner end of said short arm 307 is of sufficient weight to exactly counterbalance the longer arm 303 of the ejector lever, with all parts supported thereby. Said long arm of the ejector lever 303 is of such length that its end pin 315 coincides with the transverse axis of the jaw mechanism of the press. The 110 ejector pin is journaled by said pin 315 to the ejector link 316, jointed at its upper end by the pin 317 to the inner face of the crosshead 318, riding in the crosshead way 319, secured to the inner face of frame 1 and retained therein by strips 320. Broom hooks 321 are adapted to be interchangeably and renewably secured in the upper part of said ejector crosshead 318 by the screws 322, said broom hooks being, as indicated in Fig. 130

8 of such configuration as shall enable same to engage with the broom rings 104 upon the elongation of same under compression of the broom and thereby grip and eject the 5 latter from the press, so that said broom shall fall by gravity upon the conveyer belt 323 riding in the conveyer pan 324 secured between the paired legs 3 and 4 of the press, as indicated in Fig. 1. The sprocket-wheel 10 325 keyed upon the inner section of the clutch shaft, as indicated in Fig. 5, carries the chain 326, by which it drives the sprocket-wheel 327 mounted upon the rear end of the conveyer axle 328 which also has 15 intermediately secured thereon between the sides of the duplex leg 3 the plain conveyer pulley 329 adapted to actuate the endless conveyer belt 323 by which the finished brushes are conveyed from the press in the 20 direction of the upper arrow of said belt.

When I employ the modified form of the central structure of my invention shown by Fig. 12, in which the floor plate 124 is slid beneath instead of over the dies 96, as in 25 the arrangement shown by Fig. 8, I am enabled to feed the broom materials directly through the elongated chute 118 preferably supplied with the separating partitions, as 30 141, and dispense with the compacter 122 and the following connective members shown in Figs. 1, 7 and 8, used solely to actuate said compacter, namely: 60, 61, 129, 133, 136, 152, 154, 157, 159, 160, 161, 202, 204, 207, 208, 211, 215, 217, 221, 221^a, and 35 165, together with the connective pins and fulcra shown therewith in the views. It will be obvious, where the functions of the compacter 122 are thus dispensed with, it is desirable that the chute 118 be consider- 40 ably heightened in order to provide sufficient added gravitational momentum to the broom materials to force same through the necessarily more sharply convergent type of chute employed in Fig. 12, the greater taper 45 of which is used to replace the mechanical function of compaction exerted by the compacter 122, but it has been practically proven that such added momentum is adequate for the purpose stated and the members elimi- 50 nated by such modification of my invention tend to materially economize its cost of construction.

While the general arrangement indicated in the several views represents the preferred 55 form of my invention as actually used by me, I do not desire to restrict myself strictly to the precise members and arrangements shown, but reserve the liberty of varying the same to any reasonable degree without departing from the spirit of my invention.

The operation of my machine, largely indicated by the foregoing description of the several groups of mechanisms may be summarized as follows: When the operator has 60 received through the chute 118 a charge of

broom materials, he actuates the hand lever 114 by the handle 117, thereby first placing a ring 104, gravited from the ring chamber 121 through the ring feed plate 246 between the dies 96 and simultaneously compacting 70 the broom materials by operation of the compacter hook 157 upon the mechanism of the compacter 122. Shortly before the conclusion of said compacter operation, the slot link 133, until then running idle, makes contact with the pin 132 at the floor plate crank 129 and causes withdrawal of the floor plate 124, at the conclusion of which action, and at the end of the hand lever stroke, the tappet bolt 270, by contact with the rock 80 link 271, releases the release link 280 from its engagement behind the release crank 281, thus permitting the spring 41, as indicated in Fig. 5, to actuate the clutch lever 30 so as to throw into engagement the then still 85 clutch disk 26 with the continuously rotating clutch disk 23 constantly driven through the train of gears 16, 14, 8 and 7 by the motor 5, thus throwing into operation through the clutch shaft 22 the crank disks 90 43 and 44, the crank link 48 and the cross-head 56. During the first increment of motion of said crosshead 56, the wedge bracket 62 thereof moves away from, and the cross-head collar 59 moves toward the stationary 95 trunnion block 63, through which said cross-head 66 rises idle while the wedge cam 208 actuates, through the roll crank 204, the broom corn inserter link 215, rock lever 217, rock links 221 and 221^a, compacter links 224 100 and compacter rods 165, the compacter 122, so as to insert its compacted charge through the waiting oval broom ring 104, as indicated in Fig. 8 at the end of which vertical stroke of the compacter the contact of the 105 spring bolts 198, 199, with the frame 1 releases the detents 200, 201, so as to open the compacter for receiving its next charge.

Upon the end of the broom corn inserter stroke, the crosshead collar 59, by contact with the trunnion collar 63, imparts the power through the crosshead links 66 and 67 directly to the crank arm 70, and simultaneously through the synchronizing link 72, to the crank arm 78, thus synchronously 110 giving a straightening actuation to both cranks and compressing the materials inclosed within the broom-ring held between the dies 96, until the same shall have been given the full compression required for the 115 formation of the broom. At the end of the foregoing semi-cycle, which consumes the first 180° of the revolution of the crankpin 45, the direction of motion of said crosshead 56 being reversed, the respective crank arms 120 70 and 78 are each actuated in a direction opposite to that first imparted to them, thus moving the cranks which had been straightened by the foregoing compression operation and the press starts to open, releasing 125 130

the grip of the dies 96 upon the contained broom, which only remains sustained by the flare of its component materials, but, near the end of the outward stroke of the inner die block 86, the plunger bolt 291 (Fig. 13) makes contact with the spring bolt 293, and, through the ejector crank 297 and drop link 301, depresses ejector beam 303, carrying therewith the broom hook 321, which consequently ejects the broom with which said hook is engaged, so that it falls down upon the off-bearing conveyer belt 323. Near the extremity of the ejector stroke, the tappet bolt 330 depresses said spring bolt 293, thus permitting the plunger bolt 291 to pass thereover, as the then compressed spring 310, acting in unison with the counterpoise 314 elevates the ejector beam 303 and broom hook 321 to their first position, which return is instantaneously accomplished. Near the extremity of the outer opening stroke of the opposite die block 93, the release crank 281 makes contact with the release link 280 and throws the same inward, thereby releasing through the clutch shaft 39, the clutch crank 38 and the clutch lever 30, the clutch disk 26, from engagement with the clutch disk 23, and leaving all parts of the broom press, excepting the continuously running gear train and the motor, stationary, in readiness for the reception of another broom making charge of materials, the position of the various parts of the machine then being as indicated in Fig. 2.

Having thus described my invention, I claim:

1. A broom press comprising means of collecting a predetermined amount of broom making material, means for alining the lower ends of the broom making material, a source of broom material binder rings, means for automatically feeding the rings in successive order beneath and in vertical alinement with the collected broom material,

means for impinging against and for compressing the collected broom material and for moving the pressed material through the receiving ring below, and means for compressing the ring tightly around the collected broom material. 45

2. A broom press comprising means for collecting a predetermined amount of broom making material, means for alining the lower ends of the gathered broom material, means for moving the broom material alining means from beneath the collected broom material, a source of broom material binder rings, means for automatically feeding the rings in successive order beneath and in vertical alinement with the collected broom material, means for compressing and for moving the compressed broom material through the receiving ring below, and means for engaging and compressing the ring tightly about the broom material while in 50 a compressed condition. 55

3. A broom press comprising means for collecting a predetermined amount of broom making material, means for alining the lower ends of the collected broom material, means for moving the broom material alining means from beneath the collected material, a source of broom material binder rings, means for automatically feeding the rings in successive order beneath and in 60 vertical alinement with the collected broom material, means for compressing and for moving the compressed broom material through the receiving ring below, means for engaging and compressing the ring tightly about the broom material, and means for releasing the newly made broom and returning the parts to normal. 65

In witness whereof, I have hereunto set my hand at Indianapolis, in the county of Marion, and State of Indiana, this 29th day of December, 1916.

CHARLES H. HOWLAND-SHEARMAN.
